UNITED STATES PATENT OFFICE.

RALPH T. MUNN, OF WAKEFIELD, MASSACHUSETTS.

RIM TOOL.

Application filed February 4, 1926. Serial No. 85,918.

The object of this invention is the construction of an improved tool by means of which a split rim having attached lugs can be contracted and expanded to permit of the application thereto of a pneumatic tire.

These attached lugs are commonly four in number and are each formed with a bolt hole by means of which to fasten the rim upon the felly of the wheel.

In carrying my invention into effect I provide two oppositely threaded screw rods united by means of a turn-buckle, and having each at its outer end a finger adapted to be inserted in the holes in the attached lugs, whereby, through the turning of the turn-buckle the split ends of the rim can be separated or forced back into place again.

In the drawings forming part of this specification, Fig. 1 is a side view of a rim tool embodying my improvements. Fig. 2 is a representation of the same as applied to a split rim preliminary to the latter's contraction. Fig. 3 is a view of the same in the second step of the contraction, or as expanding the rim.

In the showing in Fig. 1, which is slightly over half-size, the turn buckle 1 receives in its ends two oppositely threaded rods 2 and 3, each having a finger 4 at its outer end adapted to enter a bolt hole 5 in one of the attached lugs 6 of the split rim 7. The rod 3 is nearly twice the length of the rod 2, and has at its approximate mid-length a second finger 9 projecting therefrom oppositely from its finger 4; the same being preferably electric-welded thereto.

The threads 10 on the two rods are not only opposite in pitch, but I prefer to have them doubled in order that the rotation of the turn-buckle shall the more rapidly act upon the two rods 2, 3.

In using this rim tool, its fingers 4 are first inserted in the holes 5 of two diametri-

cally opposite lugs 6, as shown in Fig. 2, and then the turn buckle 1 is rotated until the end 11 of the rim 7 is pulled inward and rests against the other end. The tool is next withdrawn from the holes 5 and the finger 9 is inserted in the hole formerly occupied by the finger 4 of the same rod; and the finger of the rod 2 is inserted on the next hole 5 to the right, as viewed in Fig. 3. The turn buckle is now rotated until the two ends of the rim overlap far enough to give the contraction desired. When the tire has been removed from and another slipped on over the shrunk rim, the turn buckle 1 is rotated in an opposite direction until the overlapping end is forced back into its normal position.

I prefer to locate the finger 9 at a point on the rod 3 opposite its finger 4 in order that there may be no interference with other parts of the rim or tire on the part of the fingers by either when the other is being put to use; and I prefer to have the fingers 4 rack inward slightly in order to ensure against their pulling out from the holes 5 during the contraction of the rim. To prevent their working out during the expansion of the rim, the fingers 4 and 9 are formed with notches 12 which by engaging the edges of the holes 5, provide the desired security.

What I claim as my invention is:

A rim tool comprising a turn buckle and two rods having threads of opposite pitch engaging the same, each rod having a finger at its outer end, and one rod being considerably longer than the other and having an intermediately located finger projecting therefrom.

In testimony that I claim the foregoing invention, I have hereunto set my hand this 2nd day of February, 1926.

RALPH T. MUNN.
